PRINTING PRESS

Henry A. Wise Wood, New York, N. Y., assignor
to Wood Newspaper Machinery Corporation,
New York, N. Y., a corporation of Virginia

Application February 9, 1931, Serial No. 514,376
Renewed April 19, 1934

4 Claims. (Cl. 270—5)

The present invention relates to web presses and has for an object to provide a press in which a multiple-impression unit is combined with a plurality of single-impression units.

- 5 Another object of the invention is to provide a printing press with means for printing a plurality of webs in single colors and another web in multiple colors and then interleaving the multi-colored web with the other webs, at will.
- 10 It will be understood that by the term "single-impression" unit, I refer not only to a printing unit which makes a single impression, but also to a perfecting press unit which prints first on one side of the web and then on the other, making a single impression on each face of the web. Obviously, however, since the impressions are made with separate plate cylinders provided with individual inking fountains any color of ink may be used and the color of the impression 15 on one face of the web may be different from that on the other.

In a copending application, Serial No. 512,029, filed January 29, 1931, since issued as Patent No. 1,970,929, dated August 21, 1934, I describe a 20 combined perfecting press and multicolor printing unit in which a web after being led through the perfecting unit is passed through the multicolor unit and receives a plurality of impressions in different colors. Thus, while one face of the 25 web may be printed in a single color, for instance, black, the other face may be printed with say five colors. In said application, I also provide means for reversing one press unit with respect to the other so that the multicolor 30 impressions may be made on either side of the web, as may be desired. Also in said application I show a plurality of such single and multiple-couples leading to a common folder. In the present invention, however, one multiple-impression 35 unit is combined with a plurality of ordinary perfecting press units, but means are provided to interleave the multicolor web with the other webs in any desired relation.

It is also within the purview of my invention 40 to slit the web bearing the multiple-impressions into two or more ribbons and to interleave these ribbons between the other webs at any position desired.

Other objects of my invention will appear in 45 the following description of a preferred embodiment and thereafter the novelty and scope of the invention will be pointed out in the claims.

In the drawings;

Figure 1 is a somewhat diagrammatic side 50 elevation, showing a plurality of ordinary press

units and one multiple-impression unit, all feeding webs to a single folder, with means for interleaving the multiple-impression web between any of the other webs;

Fig. 2 is a plan view of the interleaving apparatus; 5

Fig. 3 is a view in section taken substantially on the line 3—3 of Fig. 1;

Fig. 4 is a detailed view illustrating a reversing clutch for the multiple-impression unit; and 10

Fig. 5 is a diagrammatic view on an enlarged scale, of the inking mechanism for a plate cylinder of the multiple color unit, illustrating the reversing rolls used in such mechanism.

The printing press illustrated in the drawings, 15 comprises three ordinary perfecting press units A, B and C, and a multiple-impression unit D mounted over the unit A. The construction of the different units A, B and C is substantially identical and a description of the unit A will 20 suffice for the other units.

As clearly shown in Fig. 1, the unit A comprises a pair of plate cylinders 10 and 11 with their cooperating impression cylinders 12 and 13 respectively. Each plate cylinder is provided 25 with the customary inking mechanism. Between the impression cylinders 12 and 13 is a roll, 14 about which a web 15 may be led to the impression cylinders. The direction in which the web is led depends upon whether the first impression is to be made by the plate cylinder 10 or by the plate cylinder 11. In the full line position shown the web is led about the left hand side of the roll 14 and then passes between the plate cylinder 10 and impression cylinder 12. 30 From the latter the web passes around a compensating roll 16 and thence back around the impression cylinder 13 to receive the impression on its opposite face from the plate cylinder 11. When desired, the course of the web through the 35 unit may be reversed, as indicated by dotted lines, so that the web after passing about the right hand side of web 14 is led between cylinders 11 and 13 to receive its first impression, then about a compensating roll 17 and back 40 around impression cylinder 12 to receive its second impression from the plate cylinder 10.

The unit A is driven by a motor 18 preferably located above the unit, and a chain belt 19 connects the shaft of the motor to a sprocket on 45 the shaft of the impression cylinder 12.

The multiple-impression unit D which is located above the motor 18, comprises a single impression cylinder 20, about which are located four 50 plate cylinders 21, 21a, 21b, and 21c. The im-

pression cylinder 20 is driven by the motor 18 through a chain belt 22 which engages a sprocket wheel 23 on the shaft 24 of the impression cylinder 20. However, the sprocket wheel 23 is not 5 fixed to the shaft, but is adapted to be clutched thereto by a reversing clutch mechanism, so that the direction of rotation of the cylinder 20 may be reversed at will.

As shown in Fig. 4 the sprocket wheel 23 has 10 fixed thereto, a bevel gear 25 which meshes with a bevel gear 26 mounted on a fixed stud. The bevel gear 26 in turn meshes with another bevel gear 27 which also turns freely on the shaft 24. A clutch sleeve 28 is splined upon the shaft 24 15 and is formed with clutch teeth at each end adapted to engage one or the other of the cooperatively toothed inner faces of the gears 25 and 27. In the position shown in Fig. 4, the clutch sleeve is in mesh with the gear 27 and consequently the rotation of the cylinder 20 is 20 reversed with respect to that of the sprocket wheel 23. A hand lever 29 is provided by which the clutch sleeve may be slid into engagement with the gear 25 and then the drive would be direct, or, in other words, the cylinder 20 would 25 rotate in the same direction as the sprocket wheel 23.

When the impression cylinder 20 is reversed the inking mechanism for the plate cylinders 30 which coat with the impression cylinder must also be reversed. As shown in Fig. 5, the particular inking mechanism employed is of a type in which the fountain roll must always run in the same direction. The apparatus comprises the usual ink basin 30 in which is mounted a fountain roll 31. A roll 32 is adapted to pick up ink from the roll 31, and a transfer roll 33 carries the ink from the pick-up roll to the inking drum 34. Thence the ink is distributed by rolls 35 35 and 36 to the plate cylinder 21. Because of the regulating blade 37 the rotation of the fountain roll 31 and of the pick-up-roll 32 must not be reversed. Since the rotation of the plate cylinder 21 is reversed when the rotation of the impression cylinder 20 is reversed, means must be provided for reversing the inking rolls somewhere between the pick-up roll and the plate cylinder. This reversing is effected by providing an auxiliary transfer roll 38. In the position 40 shown by full lines in Fig. 5, the roll 38 is idle, but when the rotation of the cylinder 20 is in counterclockwise direction the transfer rolls are shifted from the full line position to the dotted line position, so that the ink is now transferred 45 from the pick-up roll 32 to the first transfer roll 33 and then to the second transfer roll 38 which leads it to the inking drum 34. Any suitable means may be provided for shifting the position of the transfer rolls 33 and 38.

As shown in full lines in Fig. 1, the web 15, 50 after passing successively about the impression cylinders 12 and 13, is guided past the motor by a set of rolls 40, 41 and 42, and thence is guided by a roll 43 to the cylinder 20, about which it 55 passes in clockwise direction. The web receives impressions from the plate cylinders 21, 21a, 21b and 21c in the order named and thence is guided out of the unit D by the rolls 44, 45 and 46. The web thus receives a single impression on one 60 face from the plate cylinder 10 and five impressions on the other face from the plate cylinder 11 and the plate cylinders 21 to 21c inclusive.

When it is desired to make the multiple-impressions on the opposite face of the web the latter is led about the right hand side of the 65

roll 14 and thence passes first around impression cylinder 13 and then around impression cylinder 12. From this point the web is guided by rolls 47 and 48 and then passes in reverse direction about guide rolls 45, 46, impression cylinder 20, and guide rolls 43 and 42, so that the side of the web which received its impression from the plate cylinder 10 is also printed with impressions from cylinders 21c, 21b, 21a and 21 in the order named, while the other face of the 10 web receives a single impression from the plate cylinder 11.

The web 15 after passing counter-clockwise about the impression cylinder 20 is led from the roll 42 about a roll 49 and up to a roll 50, whence 15 it is led over the unit D to the slitting and interleaving apparatus. If desired, the web which passes through the unit A need not pass through the unit D. In such case the web follows the dotted line 15a in Fig. 1 from roll 41 direct to roll 20 46. As stated above, the units B and C are substantially identical with the unit A but are not provided with rolls 47, 48 and 49 since it is not necessary to reverse the direction of the web 25 passing through these units.

The course of the various webs from the different units through the interleaving apparatus may now be traced. The web from unit A which passes through the multiple-impression unit D is indicated by the reference numeral 15, but the web from unit A which shunts the unit D is indicated by the reference numeral 15a. The webs from units B and C are indicated by the numerals 15b and 15c. The web 15 coming either from roll 46 or roll 50, passes over a drag roll 35 53 and under a slitter roll 54. Another drag roll 55 and slitter roll 56 is provided for the web 15a (should there be such a web). Similarly, a drag roll 57 and slitter roll 58 is provided for the web 15b and a drag roll 59 and slitter roll 60 40 for the web 15c. The slitter 56 slits the web 15a into two half webs or sheets 15a' and 15a''. The sheet 15a' passes over the customary compensating rolls 62 and thence over a guide roll 63 to the drag roll 64 of the folder. The other 45 sheet 15a'' may be led by the same rolls to the folder or if preferred it may be passed over turning rolls 65 and 66 so as to be directly under the sheet 15a'. Compensating rolls 67 are provided for the sheet 15a'' also, and thence it 50 passes over a roll 68 and on to the drag roll 64. Corresponding turning and compensating mechanism is provided for the other webs 15b and 15c which are slit into half webs 15b'—15b'' and 55 15c'—15c'', respectively, so that all of these half webs may be brought into superposed relation to the drag roll 64 of the folder.

As shown in Fig. 2 the web 15 is slit into two sheets 15' and 15'', and means are provided for inserting these sheets above or below any of the 60 other sheets. The sheet 15' is turned toward the left, as viewed in Fig. 3, about a turning bar 70, and then passes downward over a roll 71 outside of the other webs. The sheet 15'' is turned in the opposite direction about a turning bar 65 72 and thence passes downward over a roll 73 at the opposite side of the webs. Rolls 78, 79, 80, 81 and 82 are provided at different levels about which the sheet 15' may be introduced above or below any of the other webs or half 70 webs, and turning bars 78a, 79a, 80a, 81a and 82a are provided to turn said sheets into parallel with the said half webs. Similarly, rolls 84, 85, 86, 87 and 88 are provided for leading the sheet 15'' above or below the other half 75 webs.

webs and turning bars **84a**, **85a**, **86a**, **87a** and **88a** are provided to turn the sheet **15"** back into parallel with the other sheets.

The assembly system is thus very flexible and provides a wide variety of interleaving combinations. One of these combinations is illustrated in Fig. 2, and by full lines in Figs. 1 and 3. The half web **15b"** is turned over a pair of turning bars **65b** and **66b**, so that it runs below half web **15b'**, and similarly the half web **15c"** is turned under the half web **15c'**. One of the half webs **15'** is passed about the roll **80** and turning bar **80a** so that it is introduced between the half-webs **15b"** and **15c"**. Since there are no sheets on the right hand side of the machine, as viewed in Fig. 3, the half web **15"** must be carried over to the left hand side of the machine. Thus, as shown, the half web **15"** after passing about the roller **85** avoids the turning bar **85a**, but passes on to the turning bar **79a**. The latter is normally set at such an angle that the half web **15"**, on passing about the bar will be turned rearward, or toward the left in Figs. 1 and 2. The half web **15"** must then be passed about a roll or bar **89** to turn it toward the right. The sheet **15"** is thus introduced between the half webs **15b'** and **15b"**.

Obviously, the angle of turning bar **79a** could be reversed so as to avoid the use of the bar **89**, but it is preferable to keep the bar **79a** at its original angle so that it can be used for turning a half web **15'** forward into parallelism with the other half webs. The turning bars are mounted in the customary manner, so that they may be adjusted as desired. Thus, referring to Fig. 2, the bar **79a**, which normally lies directly over the bar **80a**, must be shifted backward to the position shown so as to bring the sheet **15"** into alignment with the half webs on the left hand side of the machine. Just beyond the turning bars for the sheets **15'** and **15"** are compensating rolls **90**, but where a bar **89** is used the compensating rolls may be dispensed with.

When the multi-color web is to be laid over instead of between or under the other webs it may pursue the course of the web **15a**. The half webs at either side of the machine may be turned under the half webs at the other side by shifting the turning bars. When desired the half webs may continue to the drag roll **64** without turning one set under the other. Hence, two folder forms **91** and **92** are provided for the left and right sheets respectively.

While I have shown a single slitter **54** for the

multi-color web, I also contemplate the use of additional slitters, as indicated in broken lines at **93** and **94**, whereby the multi-color web may be slit into a plurality of ribbons, each ribbon being interleaved wherever desired among the other sheets.

Having thus described my invention what I claim as new and desire to secure by Letters Patent is, as follows:

1. In a printing press, a plurality of perfecting press units each adapted to print a web, means for assembling the webs, a multiple impression unit adapted to make a plurality of impressions on a face of one of the webs, reversing means whereby the multiple impressions may be made on either face of the latter web as desired, and means for introducing the latter web at any desired position in the assembly. 10

2. In a printing press, a plurality of perfecting press units each adapted to print a web, means for assembling the webs, a multiple impression unit adapted to make a plurality of impressions on one face of one of the webs, and means for reversing the multiple impression unit whereby the latter web may run in either direction there- 20 through to receive multiple impressions on either face thereof, and means for introducing the latter web at any desired position in assembly. 25

3. In a web assembling mechanism, rolls for guiding a bank of webs in mutually spaced superposed relation, a slitter for slitting each web into a pair of half webs, means for turning one half web under the other, a folder for the half webs, means for guiding another web above the bank, a slitter for slitting the latter web into a pair of 30 sheets, means for leading said sheets down opposite sides of said bank, guides for introducing the sheets at any desired position in the bank, and means for turning the sheets parallel with the bank and leading them with the other half webs 40 to said folder. 35

4. In a web assembling mechanism, rolls for guiding a bank of webs in mutually spaced superposed relation, a slitter for slitting each web into a pair of half webs, means for turning one half web under the other, a folder for the half webs, means for guiding another web above the bank, a plurality of slitters for slitting the latter web into a plurality of ribbons, means for distributing said ribbons at any desired position in 45 the bank, and means for leading said ribbons together with the half webs to said folder. 50

HENRY A. WISE WOOD.
